(57) **CLAIM**

The ornamental design for a PV panel stacker, as shown and described.

DESCRIPTION

FIG. 1 is a perspective view of a PV panel stacker, showing my new design, taken from a lower portion thereof;

FIG. 2 is a perspective view, taken from an upper portion thereof; and,

FIG. 3 is a perspective view thereof, shown in environmental use.

The broken lines shown represent unclaimed subject matter and form no part of the claimed design.

1 Claim, 2 Drawing Sheets

FIG. 1

FIG. 2

FIG. 3
